UNITED STATES PATENT OFFICE.

DONALD E. LINDSAY, OF SPRINGFIELD, PENNSYLVANIA, ASSIGNOR TO MURLIN MANUFACTURING COMPANY, INCORPORATED, OF PHILADELPHIA, PENNSYLVANIA, A CORPORATION OF PENNSYLVANIA.

DESIGN FOR A BRACKET BACK FOR LIGHTING FIXTURES.

Application filed August 22, 1927. Serial No. 23,173. Term of patent 14 years.

To all whom it may concern:

Be it known that I, DONALD E. LINDSAY, a citizen of the United States, residing at Springfield, in the county of Delaware and State of Pennsylvania, have invented a new, original, and ornamental Design for a Bracket Back for Lighting Fixtures, of which the following is a specification, refer-

ence being had to the accompanying drawing, forming a part thereof, in which the figure is a view in perspective showing my new design.

I claim:

The ornamental design for a bracket back for lighting fixtures, as shown.

DONALD E. LINDSAY.
